(57) **CLAIM**

The ornamental design for a wrist splint with cutouts, as shown and described.

DESCRIPTION

FIG. 1 is a perspective rear view of a wrist splint with cutouts showing my new design;

FIG. 2 is a left view thereof;

FIG. 3 is a right view thereof;

FIG. 4 is a top view thereof;

FIG. 5 is a bottom view thereof;

FIG. 6 is a front plan view thereof; and,

FIG. 7 is a rear plan view thereof.

In the drawings, the broken lines show portions of a wrist splint with cutouts that form no part of the claim.
